BUFFING WHEEL

Howard J. McAleer, Detroit, Mich.

Application July 1, 1948, Serial No. 36,480

4 Claims. Cl. 51—193)

1

This invention relates to buffing wheels and more particularly to a buffing wheel of the type built up of a plurality of individual buffing sections.

It is an object of this invention to produce a buffing wheel which is of simple construction and therefore economical in its manufacture and which at the same time is durable and safe to use.

Another object of the invention resides in the provision of a buffing wheel in which the outer fabric buffing portions are mounted directly on rigid centering discs so that the wheel may be built up by merely arranging a number of centering discs with the attached buffing portions side by side on the spindle of a polishing lathe and clamping the sections together.

Another object of this invention is to produce a buffing wheel section in the form of a simple one piece sheet metal stamping which directly supports the fabric buffing portion and at the same time serves as a rigid centering disc for the wheel.

In the drawings:

Fig. 1 is a face view of one of the buffing sections of the wheel.

Fig. 2 is a sectional view through the buffing section taken along line 2—2 of Fig. 1.

Fig. 3 is a partial view on an enlarged scale of the cross-section shown in Fig. 2.

Fig. 4 is a partial view on an enlarged scale of the face of the wheel.

Fig. 5 is a partial end view partly in section of the composite wheel.

Fig. 6 is an elevation of the metal disc center of the buff section prior to assembling the fabric buffing portion thereto.

Fig. 7 is a view illustrating the assembly of the fabric buffing section to the metal disc center.

Fig. 8 is a fragmentary perspective showing my buffing section.

Referring to the drawings it will be seen that the wheel is made up of a plurality of individual buffing wheel sections 10 each of which comprises a round centering disc 11 having a fabric buffing portion or ring 12 secured around the periphery thereof. Disc 11 is preferably formed as a one piece metal stamping which is slotted radially around its periphery as at 13. The successive slotted portions are struck out alternately at each side of the disc so as to form two sets of offset lugs 14 which extend outwardly from the body portion 15 of the disc in a lateral and radial direction. The offset lugs 14 define a circumferential groove 16 around the outer edge of disc 11. The body 15 of disc 11 is provided with a

2

flanged central aperture 17 which receives the spindle 18 of a polishing lathe.

The buffing portion 12 of the wheel is formed from a continuous strip of bias cut fabric in a manner well known in this art. The fabric strip is first rolled lengthwise into a spirally wound hollow cylinder and then a wire 19 or other suitable fastening band is positioned over and around the spirally wound strip. The fabric cylinder is now folded radially outwardly with respect to the wire ring 19 to form the buff section 12, as shown in the drawings. As shown in Fig. 7, at this time the right hand set of lugs 14 extend at a right angle to disc 11 and the left hand set of lugs extend at about a 45° angle thereto. The fabric buff section 12 and ring 19 are now slipped over the disc 11 so that wire ring 19 is substantially in the plane of disc 11 and thereafter the lugs 14 are pressed radially outwardly and toward each other to thereby clamp the inner edge of fabric buff section 12 and wire 19 to the metal disc 11. The fabric forms a multi-layer buffing ring 12 with the inner annular edge 20 held firmly in the groove 16 by ring 19 and lugs 14 and the edges of the fabric form the peripheral face of the wheel.

It will be observed that the lugs 14 at one side of disc 11 are spaced from and staggered or offset relative to the lugs 14 on the other side of the disc. The buffing portion 12 is therefore retained firmly on the disc both by a clinching action on the part of these lugs and also by the binding action of band 19. Since the inner edge 20 of buffing ring 12 is gathered, this portion of the ring is quite thick and the thickened portions bulge out at each side of the disc in the spaces between successive lugs as shown at 26 which serves to prevent the fabric buffing ring 12 from slipping around the disc 11 even though it is not firmly clinched by lugs 14.

When it is desired to build up a plurality of these buffing sections 10 into a buffing wheel, a number of sections corresponding to the width of wheel desired are mounted on the spindle 18 of a polishing lathe, the central flanged apertures 17 serving to center each section on the spindle. Sections 10 at each end of the wheel are backed by end plates 21 which may be drawn together by means of a nut 22 threaded at the end of spindle 18. The outer face of most of the lugs 14 are provided with hemispherical depressions 23 while three or four lugs 14 at each side of the wheel are formed with hemispherical projections 24 which interengage in the depressions 23 on the lugs of the adjacent disc when the sec-

tions are nested together so that all the sections 10 are keyed together and rotate as a unit.

I claim:

1. A buffing wheel comprising a plurality of cloth layers folded into an annular buffing ring with the fold defining the inner edge of said ring, a rigid centering disc supporting the inner edge of said buffing ring, said centering disc having a central aperture for receiving a spindle and having its outer edge radially slotted to form a plurality of lugs around the periphery of said disc, the successive lugs being alternately offset, one lug on one side and the next lug on the other side of the plane of said disc to define a groove for the folded inner edge of said buffing ring, the successive lugs at each side of said wheel being spaced apart, and a ring member enclosed within the fold of said fabric layers and clamping the inner edge of said buffing ring in said groove, said inner folded edge of said buffing ring having a thickness greater than the width of said groove whereby the portion of said cloth between successive lugs on each side of said wheel bulges outwardly beyond the plane of said lugs and prevents said centering disc from rotating relative to said buffing ring, and including means formed on the outer face of said lugs for keying said disc with the lugs of a similar disc when a plurality of said discs are arranged adjacently on a spindle.

2. The combination as set forth in claim 1 wherein said keying means comprise indentations on the outer face of some of said lugs and projections on the outer face of others of said lugs, whereby a plurality of said disc may be arranged to rotate as a unit on a spindle by arranging said discs so that the projections on the lugs of one disc engage with the indentations on the lugs of the adjacent disc.

3. A buffing wheel comprising a strip of fabric wound spirally and folded circumferentially into an annular buffing ring, the outer edges of said fabric strip forming the peripheral face of said buffing ring and the folded edge defining the inner edge of said ring, a sheet metal centering disc directly supporting the inner edge of said buffing ring, said centering disc having a central aperture for receiving a spindle, the outer edge of said disc being formed into a plurality of laterally offset lugs, said lugs being spaced alternately at each side of said disc to form a peripheral channel therebetween, said folded edge being disposed within said channel and engaging said alternately offset lugs on opposite sides thereof, and a ring member enclosed within the folded edge of said

buffing ring and binding said folded edge in the channel formed by said lugs, the successive lugs being spaced apart in a direction transversely of the plane of said disc a distance less than the thickness of said folded edge, and including means on the outer face of at least a portion of said lugs adapted to engage lugs of a similar disc when a plurality of said discs are arranged on a spindle so that all of said discs rotate as a unit.

- 10 5 4. A buffing wheel comprising a plurality of buffing sections arranged adjacent one another on a spindle, each section comprising a plurality of fabric layers folded into an annular buffing ring, the folded edge of said fabric layers forming the inner peripheral edge of said buffing ring, a rigid centering disc supporting said buffing ring at said inner peripheral edge, said centering disc having a central aperture for receiving a spindle and being formed with a plurality of laterally offset 15 lugs around its outer periphery, said lugs being disposed alternately around said disc on the opposite sides thereof to form a peripheral channel around the outer edge of said disc, said folded edge being disposed within said channel with the 20 fabric engaging said lugs, and a ring member enclosed within said folded edge and clamping the inner peripheral edge of said buffing ring in said channel, said channel having a width less than the thickness of said inner folded edge whereby 25 the fabric between successive lugs at each side of said disc extends outwardly beyond the plane of said lugs, and including means formed on the outer face of said lugs for interengaging similar 30 means on the lugs of an adjacent similar disc to lock said disc together so that they will rotate as a unit when a pair of discs are arranged on a spindle with the lugs on one disc face to face with the lugs on the other disc.
